METHOD OF BLEACHING OILS AND FATS

Walter M. Urbain and Lloyd B. Jensen, Chicago,
Ill., assignors to Industrial Patents Corpora-
tion, Chicago, Ill., a corporation of Delaware

No Drawing. Application December 24, 1936,
Serial No. 117,564

5 Claims. (Cl. 260—423)

This invention relates to the treatment of fats and oils.

It is desirable in the preparation of fats and oils to produce products which are relatively light in color.

The present invention contemplates the employment of the combination of hydrogen peroxide and nitrogen salts as a bleaching agent. We have found that this combination is peculiarly effective in bleaching edible fats and oils. It may be that the utility of such mixtures resides in the formation of pernitric acid (HNO_4). In bleaching fats and oils in accordance with the present invention, we prefer to employ nitrites, sodium nitrite being particularly effective.

The utility of the present invention will be apparent by reference to Table I and Table II giving the results of the treatment of a tallow known as /S/ tallow.

20 The tallow was first cleaned by an acid wash followed by agitation with fuller's earth and a small amount of decolorizing carbon, after which the cleaned tallow was filtered. In bleaching the fat, the hydrogen peroxide and sodium nitrite were dissolved in about 10 cc. of water which was added to 100 gm. of the fat which had been previously heated to about 60° C. and was in liquid condition. The mixture was vigorously agitated for a few minutes and then was allowed

30 to stand for several hours at a temperature of from 35° C. to 40° C.

Bleaching action from the combination of hydrogen peroxide and sodium nitrite is apparent in a few minutes, although it is preferable to let 35 the mixture stand for several hours to render reasonably certain that all bleaching value of the bleaching agents is obtained.

Table I

Sample	Gm. hy- drogen peroxide	Gm. sodium nitrite	FAC reading N. D. T.
5 1.	0.0	0.0	41
2.	0.3	0.4	33
3.	0.9	1.2	21
4.	1.5	2.0	21
5.	0.3	-----	39

0 Table II indicates the results of an experiment on another batch of the same /S/ tallow.

Table II

Sample	Gm. hy- drogen peroxide	Gm. sodium nitrite	FAC reading N. D. T.	
1.	0.0	0.0	43	5
2.	0.3	0.3	43	
3.	1.0	-----	43	
4.	0.9	0.3	31	
5.	0.9	1.0	33	
6.	0.9	-----	37	10

It is apparent from the data of the foregoing tables that the combination of hydrogen peroxide and sodium nitrite gives results greater than the sum of the results of sodium nitrite and hydrogen peroxide when used separately, sodium nitrite when used alone being ineffective.

15 Sample 4 of Table I was converted to the sodium soap and the fatty acids liberated subsequently with sulphuric acid. The reading of the N. D. T. 21 was unchanged indicating no change of color upon saponification.

20 The present invention provides a simple, inexpensive and effective method for bleaching fats and oils.

25 In the claims, the term "oil" is used in the broad sense to include both fats and oils separately or in mixtures.

We claim:

1. The method of treating oil which comprises 30 adding thereto hydrogen peroxide and a nitrite.

2. The method of treating oil which comprises adding thereto hydrogen peroxide and sodium nitrite.

3. The method of bleaching oil which comprises 35 adding a solution of sodium nitrite and hydrogen peroxide to the oil, agitating the mixture to secure intimate admixture, and permitting the oil to bleach.

4. The treatment of oil which comprises adding from 0.3 per cent. to 1.5 per cent. hydrogen peroxide and from 0.4 per cent. to 2.0 per cent. sodium nitrite to the oil.

5. The treatment of oil which comprises adding from 0.3 per cent. to 1.5 per cent. hydrogen peroxide and from 0.4 per cent. to 2.0 per cent. sodium nitrite to the oil, agitating the mixture to secure intimate admixture, and permitting the oil to bleach.

WALTER M. URBAIN. 50
LLOYD B JENSEN.
